UNITED STATES PATENT OFFICE

2,439,225

WORKPIECE FEEDING DEVICE FOR CENTERLESS GRINDING AND LIKE MACHINES

Arthur Scrivener, Birmingham, England

Application February 15, 1945, Serial No. 578,049
In Great Britain February 24, 1944

1 Claim. (Cl. 51—103)

1

This invention has reference to improvements in workpiece feeding devices for centreless grinding and like machines, more particularly to machines in which a complementary pair of rotary bodies are adapted to operate upon the workpiece introduced therebetween onto which workpiece a surface operation, such as peripheral grinding, thread milling, cutting or rolling, has to be performed.

The object of the present invention is to introduce the workpieces successively into the operative position by means of a feed carrier device which is desirably continuous or intermittently continuous in its operation, which carrier shall have provision for loading and unloading the workpieces at points removed from the operative point so as to increase the speed of operation of the machine and facilitate the introduction of the workpieces in succession thereto.

The invention consists of a workpiece feeding device for use in connection with centreless grinding and like machines, comprising a notched carrier member which passes the workpieces in succession between the presented operative peripheries of the wheels or rollers of the machine. The said carrier member desirably comprises an annulus the axis of rotation of which is disposed parallel to or substantially parallel to the axis or axes of rotation of the wheels or rollers which operate upon the workpieces, but in certain kinds of machines it may be desirable to locate the axis of the annulus at a convenient angle to the axis or axes of the operative wheels.

The invention further resides in details in the construction and location of the carrier member or ring whereby a continuous or substantially continuous feeding of the workpiece to and from the operative point of the machine obtains, and in means for effecting the automatic release of the workpieces from the carrier member.

The invention will now be described in a preferred form as applied to a centreless grinding machine.

In the drawings:

Fig. 1 is an end elevation of the mechanism comprising the present invention.

Fig. 2 is a cross sectional elevation of part of the mechanism seen in Fig. 1.

The workpieces *a* to be ground are located at intervals in evenly spaced notches *b*¹ formed in a carrier ring *b*, the ring having its axis of rotation located parallel or substantially parallel to the axis of rotation of the grinding wheel *c* and of the control wheel *d* by means of which the workpiece is held up to the periphery of the grinding

2

wheel (see more particularly the workpiece *a*^x in Fig. 1). This notched carrier ring *b* has rotation in a path which is eccentric to the path of rotation of the periphery of the control wheel *d* about which the notched carrier ring is located. The carrier ring *b* passes between the presented peripheral faces of the grinding wheel *c* and the control wheel *d* and is of lesser thickness than the diameter or outline dimensions of the workpieces 10 *a* so that the workpieces will extend beyond the inner and outer peripheries of the notched carrier ring *b*. This notched carrier ring is mounted on and adapted to rotate about a circular track *e* which is gapped at *e*¹ near the top thereof, which 15 gap provides an automatic or gravity release for any workpiece carried thereover by the notched carrier ring *b*. The circular track *e* is also gapped at *e*² to provide a passage for the location of part of the periphery of the control wheel *d* so that 20 this wheel may be accurately positioned together with a workpiece relative to the grinding wheel *c*.

Workpieces are successively introduced into the notches in the carrier ring *b* either by hand or automatically through a supply hopper, conveyor or other feeding mechanism (not shown) 25 so that the workpieces *a* are carried by the rotation of the notched carrier ring *b* to the operative point for each workpiece between the presented peripheral faces of the grinding wheel *c* and the control wheel *d* (see the position of the workpiece *a*^x in Fig. 1). After being ground each workpiece by the continued rotation of the notched carrier ring *b* is conveyed to the gap *e*¹ and the piece so disposed is released through the 30 gap *e*¹ in the circular track *e* and delivered into the channel *f* which directs or delivers the released workpiece.

Advantageously the notches *b*¹ in the carrier ring *b* are of a greater width than the diameter 40 of the workpiece *a* to be ground so that there is provided a freedom of motion between the workpiece and the carrier ring at the working or operative point. By this means a continuous rotation may be imparted to the carrier ring without adversely affecting the accuracy of the grinding operation to be performed on the workpiece, but alternatively the carrier ring may be subjected to 45 intermittent rotational motion, the motion steps coinciding with the distance obtaining between the notches in the carrier ring.

It will be appreciated from the foregoing description that an important feature of this invention is the disposition or location of the notched carrier ring *b* between and relative to the 50 presented peripheries of the grinding wheel *c* and

and the control wheel *d*, and that this disposition or location is accomplished by the parallel or substantially parallel arrangement of the axes of all of these rotational parts, but in a modification the axis of rotation of the carrier ring may be 5 at right angles or any other convenient angle to the axis of the grinding and control wheels.

I claim:

A feeding device for centreless grinding and like machines which have a grinding roll and an opposed control roll, comprising a carrier ring which passes between the rolls and has a thickness less than the normal distance between the rolls, means for rotating the carrier ring upward between the rolls, retaining rings on both sides of and concentric with the carrier ring which have gaps to leave clearance for the rolls and which are spaced apart slightly more than the normal distance between the rolls, and notches in the carrier

ring each of which holds a workpiece to be passed between the rolls, has its trailing side inclined toward the control roll and is substantially wider than the workpiece, whereby during rotation of the carrier ring the workpiece rests against a retaining ring until it reaches the gap therein and then falls against the control roll.

ARTHUR SCRIVENER.
